STILL FILLING AND DEAERATING MACHINE

Albert M. Armstrong, Los Angeles, and Otto M. Clinton, Glendale, Calif.; said Clinton assignor to said Armstrong

Application March 26, 1940, Serial No. 326,028

10 Claims. (Cl. 226—116)

The primary object of our invention is the production of a new, novel and useful still filling and de-aerating machine semi-automatic in action, and of structural characteristics embodying features uncommon to the art, and embracing a machine which may readily be constructed of varying capacity for the simultaneous filling of a multiple number of containers, regardless of shape, size and capacity.

A further object of the herein invention is the provision of a machine of said type presenting a multiple number of improvements in its operating mechanism, and whereby a simple direct controlled feed means is provided, the feed mechanism involving an ingeniously devised distribution system, automatic in action for the filling of a multiple number of bottles on manual manipulation of the operating mechanism.

A further object of the herein invention, resides in the provision of a machine of this character in which all of the operative parts are arranged compactly in a main supporting frame, with simple and improved driving or operating means, and which supporting frame may be constructed in sectional units for operating engagement to one another.

A further object of the herein invention resides in the provision of a machine possessing advanced ideas and advantages for maintaining the same at all times and under all conditions, in a thoroughly hygienic state.

A further highly important object of the herein invention is the provision of a machine in which the de-aerating process is accomplished momentarily prior to the filling process, air within the bottle to be filled being simultaneously removed under vacuum, and the liquid in the filling process diffused as a fine spray which trickles down the sides of the bottle to further enhance de-aeration.

A further object of the herein invention is the provision of a machine wherein the feed heads, at all times emit no drip, and whereby the exterior surface of the bottles before, during and after the filling operation remain dry and clean, unsmeared by drip or over splash, more or less common with filling machines in use.

A further object of the herein invention comprises a means for automatically under manual control, aligning the bottles to be filled with the filling heads, and for placement of said heads in juxtaposition for the filling operation.

And a further object of the herein invention is to provide a machine of said characteristics through the instrumentality of which three or

more bottles may be simultaneously filled, and also permitting engagement of a number of machines to be operably connected and controlled from a single source.

Other objects and advantages of the invention will more fully appear as this specification proceeds and as is set forth in the appended claims.

We attain these objects by the machine disclosed in the accompanying drawings; in which:

Figure 1 is an elevation of our invention,

Figure 2 is a section on line 2—2 of Figure 1;

Figure 3 is a section on line 3—3 of Figure 1;

Figure 4 is a section on line 4—4 of Figure 1;

Figure 5 is a section on line 5—5 of Figure 1 with certain parts broken away,

Figure 6 is a section on line 6—6 of Figure 1 on a larger scale,

Figure 7 is a section on line 7—7 of Figure 1,

Figure 8 is a view similar to Figure 7 but with certain parts in a different position,

Figure 9 is a view similar to Figures 7 and 8 but with certain parts in a still different position, and

Figure 10 is a section on line 10—10 of Figure 1.

Similar letters and numerals of reference indicate like parts throughout the several views. The machine assembly thus comprises a framed table structure T having legs 11, and a lower shelf 12. Additionally standards 13 extend above the legs and are joined by bars 14 in engagement therewith tying their upper ends in a fixed position so as to form a pair of frames 15 and 16 at opposite ends of the standards.

Each of the bars 14 has a lug 17 formed on the side to provide support for a vertical screw 18 which has a sprocket 19 secured thereto. The sprockets are connected by a chain 20 which serves to turn the opposite screw whenever either screw 18 is rotated, a squared end 21 in each screw providing a means for engagement of a wrench for rotation of the same. The screws 18 are threaded through lugs 22—22 formed upon bearing blocks 23 which are thereby vertically adjustable upon the standards of the frames 15 and 16.

Said bearing blocks 23 carry a shaft 24 having crank arms 25 secured at opposite ends thereof. The arms 25 are connected by links 26 to movable blocks 27 which have machined bifurcations at opposite ends so that said blocks are vertically slidable between the front and rear standards 13 of the frames 15 and 16.

Valved filler heads 28 are suspended between the frames 15 and 16 by bars 29 and 30 which are secured at opposite ends upon the blocks 27

by bolts 31 and tie blocks 32, as shown in Figure 6, bars 29 and 30 are spaced slightly apart so that a reduced top end 33 of the filler heads may be secured between said bars by a bolt 34. This bolt may be loosened and the filler heads moved along between the bars 29 and 30 whenever it is desired to change the distance between said heads for the accommodation of bottles of varying widths.

Each of the blocks 27 has an extension 35 of one of the rear bifurcations to support a pair of manifolds 36 and 37 as shown in Figures 5 and 10.

Each of the heads 28 is connected by a flexible conduit 38 to the manifold 36 and by a flexible conduit 39 to the manifold 37 as is shown best in Figure 10.

The manifold 36 is plugged at one end but has the other end connected by a flexible conduit 40 and pipe fittings 41 to a tank 42 secured upon the shelf 12. Said tank may be of glass so as to readily disclose the contents thereof.

Pipe fittings 43 connect said tank 42 and a three-way valve 44, which has one opening 45 unconnected or open to the atmosphere, and its third opening 46 connected to a pipe 47 in turn engaging a T 48 in engagement with a nipple 49 which is coupled to a vacuum pump 50.

The vacuum pump is further connected to an air exhaust chamber 51. A tube 52 by means of a reducing coupling 53 is connected at one end with said T 48, and at its other end is connected to a cylinder 54, as shown in Figure 5. Said cylinder is pivotably mounted at one end upon the frame T by means of a pin 55. Within said cylinder, a piston 56 is operably positioned, the piston rod 57 being suitably connected at one end by pin means 58 to one end of a crank arm 59. Said arm is adjustable as to length by means of bolts 60 in engagement with slots 61 therein disposed, and at its other end, it is attached to the shaft 24.

A crank arm 62 is attached at one of its ends to said shaft 24, and at its other end by means of a bolt 63 to a weight 64. The manifold 37 is plugged at one end. Its other end is connected to a flexible conduit 65 which extends into a barrel 66 or like container forming the source of supply of liquid to be transferred to bottles or the like.

A conduit 67 has one end in the barrel and the other suitably connected to one side of a pump 68. The other side of the pump is connected by a conduit 69 to a check valve 70 which is in turn by means of a nipple 71, T 72, and nipple 73 connected to the bottom of the tank 42.

The pumps 50 and 68 are respectively mounted upon the shelf 12 and are driven by belt means 75 and 76 respectively and a motor 77 which is also mounted on the shelf 12.

A channel bar 78 is secured to and supported upon the frame T and serves to support and guide an endless conveyor 79 fed around pulleys or sprockets 80 and 81 supported by bearing blocks 82 and 83 respectively which are suitably attached to opposite ends of the bar 78.

An elongated plate 84 is suspended beneath the bars 78 by hangers 85 and serves to support the lower run of the conveyor 79.

A shaft 86 is suspended beneath the plate 84 by hangers 87 and has crank arms 89 and 90 attached adjacent its opposite ends. A linkage 88 transmits the motion of the shaft 86 to the valve 44.

A rod 91 is provided parallel to and of approximately identical length with the shaft 86. 75

It is, however, located above the bar 78. Its respective ends are secured in slidable blocks 92 which are located in slots 93 provided in supports 94 mounted on the frame as shown in Figure 5.

5 The arms 89 and 90 have slots 95 at their upper ends through which bolts 96 connect said arms to the blocks 92.

A handle 97 of a lever 98 is slidably carried by a lug 99 provided upon the side of the arm 90 and is normally urged upwardly by means of a spring 100.

The lower end of the lever 98 is slotted at 101 to permit a downward sliding movement of the lever. The shaft 86 extends through said slot 101. The lever 98 carries a lug 102 at its lower end which at certain times hereinafter explained engages a pin 103 fixed in a bracket 104 secured to frame T.

A leaf spring 105 has one end attached to the arm 90 and the other end free to engage and press a switch button 106 protruding from a switch box 107 which may be secured at one end of one of the supports 94 adjacent the arm 90.

The switch box may contain any kind of contact switch, but a bracket 108 is shown secured to an insulation block 109 which is secured in the switch box. The bracket supports one end of a screw 110 having the other end threaded into the switch button 106 which is of insulating material and is normally urged outwardly by a spring 111.

Another bracket 112 is provided having a hole 112' which is large enough for the screw 110 to pass through without contacting the bracket.

35 One wire lead of an electric cable 113 is soldered to the bracket 108 and another to the bracket 112 so that when the switch button is released the head of the screw contacts the bracket 112 completing the circuit for energizing a motor M.

40 The sprocket 81 is driven through a belt 114 from a reduction box 115 containing gears (not shown) which may be driven by means of a belt 116 from the motor M.

A plurality of blades 117 are attached to the rod 91 and as shown in Figure 2, these are gradually reduced in length from the first blade at the right.

45 Guide rails 120 are provided and may be supported by the angle irons 85' adjustably attached to hangers 85 so that bottles of various width may be fed between said guide rails.

Referring to Figure 6, it will be seen that the valvular filler heads embody a cylinder 121 open at the bottom to receive a plunger 122 limited in 55 its movement by a screw 123 threaded into the plunger through a slot 124 in the side of the cylinder. The plunger is normally urged outwardly from the cylinder by a spring 126 which takes up the shock when the heads are dropped so as to contact the bottles, which shock, however, is extremely light since the drop is not extensive. A slot 127 is provided in one side of the cylinder permitting nipples 128 and 129 to be threaded into the side of the plunger 122. The 60 nipple 128 is threaded into a chamber 130 in the upper end of the plunger.

A hollow stem 131 is threaded upwardly in the plunger so as to connect at the upper end with the chamber 130. The lower end of the stem 131 is threaded to suspend a connection 132 having a shorter stem 133 threaded upwardly into it. Said stem 133 is made removable to permit stems of various lengths to be substituted for reasons hereinafter explained.

75 A nipple 134 is threaded into the bottom of the

plunger to connect with a chamber 135 in the plunger. Said chamber 135 is in communication with the nipple 129. The stem 131 extends down through the nipple 134 but the outside diameter of the stem is not as great as the inside diameter of the nipple, thereby providing an annular passage-way 136 between them.

Ports 137 are provided adjacent the lower end of the nipple 134 which abuts a shoulder 138 of the connection 132. A sleeve 139 is provided closely surrounding the nipple 134 and is adapted to reciprocate freely from end to end of the nipple to open and close the ports 137. The diameter of the sleeve at the upper end is identical with that of the plunger, but is spaced from the plunger by a sealing washer 140 provided about the nipple 134. The lower end of the sleeve is of a reduced outside diameter to permit entry into a small mouthed bottle, as shown by way of example, in Figure 6 as the neck of a bottle B.

A gasket 141 of soft rubber or similar material surrounds the reduced diameter of the sleeve. It is prevented from falling off because of a snug fit.

In operation, the machine is first set to correctly and securely hold the bottles during the filling process. To accomplish this, a few bottles are placed on the conveyor directly under the filler heads, after which the bottle adjustment guides and filler head supporting structure as aforementioned are regulated to the size, shape and height of the bottle in manner already explained.

The filling operation proper is accomplished in the following manner.

We shall assume that the bottles B shown in the drawings are being filled while the conveyor 19 is stationary. During said filling process, an additional supply of empty bottles (not shown) are placed on the conveyor to the right of the bottles which are in filling position. When the bottles under the heads are full, the operator pulls back on the handle 97 until the lug 102 of the lever 98 engages the pin 103, as shown by dashed lines in Figure 5. As the lever 98 is carried by lug 99 on the crank arm 90, the latter will move with the lever and turn the shaft 86 which moves the valve 44 by means of the linkage 86' to the position shown in Figure 8.

The suction of the vacuum pump is now applied by means of the tube 52 to the cylinder 54 drawing the piston 56 down so that the rod 57 and the arm 59 will turn the shaft 24 in a clockwise direction as seen in Figure 5.

The arms 25 are thereby moved to lift the blocks 27 carrying the heads 28 by means of the bars 29 and 30. The vacuum pump is assisted in this movement by the weight 64 which partially counterbalances the parts connected to the piston. As the heads are lifted the sleeve 139 drops down by gravity to close the ports 137 and thereby prevents dripping of liquid from the head. The handle is still in position so that the spring 105 still presses on the switch button, thereby preventing a completed electrical circuit in the switch box.

When the heads are lifted free from the bottles the operator presses the handle 97 downwardly overcoming the resistance of the spring 100 until the lug 102 is low enough to pass beneath the pin 103 permitting the handle to be drawn all the way back until the blocks 92 reach the outer end of the slots 93. At this time the spring 105 no longer engages the switch button so that a completed circuit is formed in the switch box to en-

ergize the motor M to move the conveyor, carrying the full bottles to the left (see Figure 1) out of the filling section of the machine, and simultaneously therewith, moving the assembled unfilled bottles from the right side of the machine as aforementioned, into place within the filling section for proper alignment and filling in repetition of the filling operation. During the foregoing movement of the bottles, the valve 44 is moved to the position shown in Figure 9, so that the suction of the vacuum pump is still applied to the piston 56, holding the heads up while the conveyor is moving.

When the empty bottles reach a point approximately beneath the heads, the operator pushes the handle 97 back to the full line position shown in Figure 5 which moves the valve 44 back to the position shown in Figure 7, thus breaking the vacuum in the tube 52 which causes the heads to drop down by their own weight to the position as is fully disclosed in the drawings, and opening the ports 137.

Simultaneously with the movement of the handle 97 backwardly, the arms 89 and 90 move the rod 91 toward the bottles and cause the blades 117 to align the bottles in their correct position under the filling heads, said blades easing the bottles over one at a time due to the graduated length of the blades, the entire sequence of aligning the bank of bottles being accomplished in a second.

With the valve 44 now in the position disclosed in Figure 7, suction is applied by the vacuum pump to the pipe 47, valve 44, fittings 43, tank 42, fittings 41, conduit 40, manifold 36, conduits 38, nipples 128, chambers 130, stems 131, stems 133, bottles B, nipples 134, chambers 135, nipples 129, conduits 39, manifold 37 and conduit 65, thus drawing the liquid up from the source of supply barrel 66 into the bottles.

If the operator does not attend to the apparatus when the bottles are full, the liquid is drawn up into the stems 133 and 131 and back through the conduit 40 into the tank 42, and thereby providing a safety factor. The pump 68 will at the same time draw off the liquid, if any, in said tank 42 contained, and convey it by means of the conduit 67 back into the barrel 66.

When the operator notices that the bottles are full, the handle 97 is again pulled back to the broken line position of Figure 5, and the operation is continued as above described.

As described, the valve 44 is moved into the position of Figure 8, breaking the vacuum in the bottles so that liquid is no longer drawn up and the sleeves 139 drop down over the ports 137 as the heads are drawn up, preventing dripping.

The stem 133 is made removable so that a shorter or longer stem as required may be substituted to limit the height of the liquid drawn into the bottles.

As the liquid is drawn into a bottle from the ports 137, the liquid rises until it reaches the bottom of the stem. At this point no more liquid will stay in the bottle, for it will be drawn up into the stem instead and as aforementioned into the tank 42.

The entire filling and removing operation of a plurality of bottles in each operation, takes but a short space of time. Rapidity in operation is thus an important feature of our machine.

It is practically fool proof, has no working parts which may readily get out of order, or disclose excessive wear, and in its component structure, it

presents a well built and compactly assembled entirety.

Readily produced from materials obtainable in the open market and at no great cost, our invention in its design and simplicity of operation and satisfactory service rendered, marks for a decided advance in the bottle filling machine art.

It should be understood that while we have herein for the sake of simplicity confined ourselves to the term "bottle," that any other suitable type of container may as readily be employed, and to this end we do not confine or limit our invention exclusively to a "bottle" filling machine.

We are further aware that slight modifications may from time to time be made in the details of structure shown without departing, however, from the scope of the present disclosure, and as defined in the claims which are appended hereto. Hence, we do not limit our present invention to the exact description of construction shown, but what we do claim is:

1. In a machine for filling containers, a frame, a plurality of filling heads mounted on the frame for movement into and out of filling position, a conveyor on the frame for moving containers into and out of position to be filled, a source of supply of liquid, a liquid supply line for connecting said heads with said source of supply, a vacuum pump, a vacuum line for connecting said pump with said heads; each of said heads including tubular members adapted to be extended into a container to be filled and being provided with means operable for evacuating the container and introducing liquid into the container during operation of said pump, means responsive to said vacuum pump for lifting said heads out of filling position and also operable to permit the heads to gravitate into filling position, and valve means for controlling said vacuum line to said heads, a manually operable means for said valve means, a motor for operating the conveyor, and a circuit closer for controlling said motor responsive to manipulation of said manually operable means.

2. In a machine for filling containers, a frame, a plurality of filling heads mounted on the frame for movement into and out of filling position, a conveyor on the frame for moving containers into and out of position to be filled, a source of supply of liquid, a liquid supply line for connecting said heads with said source of supply, a vacuum pump, a vacuum line for connecting said pump with said heads; each of said heads including tubular members adapted to be extended into a container to be filled and being provided with means operable for evacuating the container and introducing liquid into the container during operation of said pump, a series of aligning blades movable on the frame into and out of position between and for aligning the containers with said heads, and a valve means for controlling said vacuum line including a valve operating handle, and means responsive to movement of said handle for moving said blades into and out of position for aligning the containers with said heads.

3. In a machine for filling containers, a filling head including a body, a pair of concentric tubular members each fixed at its upper end within and depending from said body and adapted to be extended into a container to be filled, means embodied in said body between the ends thereof providing for connection of said members with a vacuum pump and a source of supply of liquid, respectively, one of said members extending be-

low the other and open at its lower end for evacuating the container, the other member having a port for discharging liquid from said source into the container, a sleeve device mounted on the last named member below the plane of the lower end of the body and so as to be moved out of position closing said port upon contact with said container when inserting said tubular members into the container, and adapted to gravitate into port closing position when the tubular members are withdrawn from said bottle, said sleeve device including a compressible gasket adapted to yieldingly contact and close the mouth of the container, a cylinder in which said body is movable and spring means within the cylinder resisting movement of said body upon contact of said gasket with the container.

4. In a machine for filling containers a frame, means thereon for supporting containers in position to be filled, a filling head support vertically adjustably mounted on said frame, a plurality of filling heads on said support, lever means for raising and lowering said support including fulcrums vertically adjustable on and relative to the frame, adjusting means for moving said fulcrums relative to said frame to set said heads at different levels on said frame to accommodate the machine to containers of different sizes, and means operating first to move said lever to raise the heads out of bottle filling position and thereafter to release the heads for gravitation into filling position, including a fluid operated cylinder pivoted on said frame, and a plunger operable in the cylinder and pivoted to said lever means.

5. In a machine for filling containers a frame, means thereon for supporting containers in position to be filled, a filling head support vertically adjustably mounted on said frame, a plurality of filling heads on said support, lever means for raising and lowering said support including fulcrums vertically adjustable on the frame, adjusting means for setting said fulcrums on said support and said heads on different levels on said frame to accommodate the machine to containers of different sizes, means for rocking said lever to raise the heads out of bottle filling position and then release said lever means whereby the support and heads may gravitate into filling position, vacuum means associated with said heads for effecting a container evacuating and bottle filling action of said heads including a vacuum pump; said means for rocking said lever means including a vacuum cylinder connected with said pump, a piston in said cylinder connected with said lever means, and valve means for controlling the operation of said heads and said piston.

6. In a machine for filling containers a frame, means thereon for supporting containers in filling position, a plurality of filling heads movable into and out of filling position on said frame, a source of supply of liquid, a liquid supply line connecting each head with said supply, a tube on each head, connected with said supply line and adapted to extend into a container and having a liquid outlet port, a tank, a vacuum pump connected with said tank, a vacuum line for connecting said heads with said tank, an evacuating tube in each head extending thru said liquid supply tube and adapted to extend a greater distance into the container than said liquid supply tube and being connected with said vacuum line at its upper end and open at its lower end, a pipe line for returning liquid from the tank to the source of supply and a pump for pumping liquid thru said return line to said

source of supply, a vacuum operated device responsive to the vacuum pump for lifting said heads out of filling position and for releasing said heads for gravitational movement into filling position and a valve for controlling said vacuum pump, selectively operable for communicating the evacuation line with said heads, operating means for said valve, and means for moving said container supporting means to bring containers into and out of filling position responsive to predetermined operation of said valve operating means.

7. In a machine for filling containers, a frame, a bottle filling head mounted on the frame for movement into and out of bottle filling position, a source of supply of liquid, a liquid supply line from said source to said head, a vacuum pump associated with said head for drawing liquid therethrough, a conveyor for moving containers into and out of filling position with respect to said head, a vacuum responsive lifting means for raising said head out of filling position upon operation of said pump and for releasing said head for gravitational movement into filling position, a valve for controlling said pump for selectively and simultaneously actuating said head and said raising means, operating means for said valve, and means for operating said conveyor responsive to movement of said valve operating means.

8. In a machine for filling containers, a frame, a bottle filling head mounted on the frame for movement into and out of bottle filling position, a source of supply of liquid, a liquid supply line from said source to said head, a vacuum pump associated with said head for drawing liquid therethrough, a conveyor for moving containers into and out of filling position with respect to said head, a vacuum responsive lifting means for raising said head out of filling position upon operation of said pump and for releasing said head for gravitational movement into filling position, a valve for controlling said pump for selectively and simultaneously actuating said head and said raising means, operating means for said valve, and means for operating said con-

veyor responsive to movement of said valve operating means, said valve operating to maintain the raising means in operation while the conveyor is moving and being thereafter operable to render said raising means inoperative so that the head may gravitate into filling position and to connect the head with said vacuum pump.

9. In a machine for filling containers a frame, means thereon for supporting containers in position to be filled, a plurality of filling heads arranged in a row on the frame and with which the containers must be aligned in order to be filled, a blade supporting member slidable on the frame, a row of spaced parallel blades carried by said member and adapted to be extended between containers to align them with said heads, said blades beginning at one end of the row thereof being gradually reduced in length toward the other end of the row whereby to successively engage the containers for aligning them with the heads one at a time, and means for moving said blade support for extending and retracting the blades.

10. In a machine for filling containers a frame, means thereon for supporting containers in position to be filled, a plurality of filling heads arranged in a row on the frame and with which the containers must be aligned in order to be filled, a blade supporting member slidable on the frame, a row of spaced parallel blades carried by said member and adapted to be extended between containers to align them with said heads, said blades beginning at one end of the row thereof being gradually reduced in length toward the other end of the row whereby to successively engage the containers for aligning them with the heads one at a time, and means for moving said blade support for extending and retracting the blades, including a lever fulcrumed on the frame and connected with said support, and means for operating said heads, including a valve controlled by movement of said lever for controlling the operation of said heads.

ALBERT M. ARMSTRONG.
OTTO M. CLINTON.
